UNITED STATES PATENT OFFICE.

FREDERICK TOOMEY, OF BALTIMORE, MARYLAND.

WELL-BUCKET ROPE-HOLDER.

SPECIFICATION forming part of Letters Patent No. 430,409, dated June 17, 1890.

Application filed February 4, 1890. Serial No. 339,187. (No model.)

To all whom it may concern:

Be it known that I, FREDERICK TOOMEY, a citizen of the United States, residing at Baltimore, in the State of Maryland, have invented 5 certain new and useful Improvements in Well-Bucket Rope-Holders, of which the following is a specification.

This invention relates to a holder for the rope of well-buckets.

10 The construction and combination whereby the desired result is accomplished will be described in connection with the accompanying drawings, in which—

Figure 1 is a side view of my invention as 15 applied to a rope and two buckets in a well. Fig. 2 is a top view of the rope-holder. Fig. 3 is a sectional side view of the same.

The letter A designates the supporting-frame, of any suitable construction, and B the well-curb. At a sufficient height of the supporting-frame A is a cross-piece c, to which is attached the rope-holder D. This holder consists of a plate having a slot e nearly its entire length, and at each end a rope-hole f, 25 which is separated from the central slot by a bridge-piece g. A pawl or gripper h has one end secured in the central slot at a point midway between its ends by a pivot-bolt i. Its free end has a serrated head h' to press against 30 the rope. This pawl may be turned on its pivot i, so as to present its head h' in either

direction, and when in action this head will be in contact with that portion of the rope K which is moving upward, as shown by the dart.

Two buckets P are used, one being secured 35 to each end of the rope K, the latter passing over a wheel Q, secured at the top of the frame A.

The serrated end h' of the pawl h should be placed against the ascending part of the 40 well-rope. If, for any reason, the person raising the filled bucket should let go the rope, the pawl h would grip or squeeze the rope against the end of the holder-plate, and thereby would prevent the filled bucket from descending. When the opposite bucket is let 45 down and filled, the pawl is then thrown over to engage with the rope at the other end of the holder-plate.

Having described my invention, I claim— 50

The combination of the rope, the pulley-wheel, a plate having at each end a rope-hole, and a pawl or gripper having one end secured to said plate by a pivot-bolt midway between the two rope-holes, for the purpose set forth. 55

In testimony whereof I affix my signature in the presence of two witnesses.

FREDERICK TOOMEY.
